UNITED STATES PATENT OFFICE.

ANTHONY MARUCA, OF ANITA, PENNSYLVANIA.

MONOPLANE.

1,191,448.

Specification of Letters Patent. Patented July 18, 1916.

Application filed October 17, 1914. Serial No. 867,150.

To all whom it may concern:

Be it known that I, ANTHONY MARUCA, a subject of the King of Italy, residing at Anita, in the county of Jefferson and State of Pennsylvania, have invented certain new and useful Improvements in Monoplanes, of which the following is a specification.

This invention relates to flying machines of the heavier-than-air variety and more 10 specifically relates to that type of aeroplane commonly designated as a monoplane by reason of its single supporting surface.

As a principal object, this invention contemplates the provision of a monoplane 15 which shall be constructed with regard to a novel adaptation of the "dihedral angle construction" of the supporting surface.

A coördinate object is to incorporate with the novel surface of the type described 20 warpable wing tips readily controllable by the operator to increase the angle of incidence of the wing tips in the well-known manner.

It is a further object to provide a following tail-plane simultaneously controllable 25 by the steering means for the usual rudder and acting as an auxiliary stabilizing mode in conjunction with the wing tips.

It is an object of equal importance to provide 30 a specific arrangement of a monoplane of the type described which in addition to embodying the previously mentioned features will be so constructed as to present the utmost simplicity of design consistent with 35 its efficiency and durability in operation.

The above and additional objects which will become apparent as this explanatory description proceeds, are accomplished by such means as are illustrated in the accompanying 40 drawings, described in the following specification, and then more particularly pointed out in the claims which are appended hereto and form a part of this application.

With reference to the drawings, wherein there is illustrated the preferred embodiment of this invention as it is reduced to practice, and throughout the several views of which like characters of reference designate 50 similar parts: Figure 1 is a front elevation of a monoplane constructed to embrace the particular features of this invention, Fig. 2 is a plan view of the matter shown in Fig. 1, a small portion being necessarily 55 broken away, Fig. 3 is a side elevational

view, and Fig. 4 is a detail perspective view of the following tail plane removed from the plane. Fig. 5 is a detail view of the operating lever for operating the wing planes.

In modern aeroplane design, attention is chiefly directed to rendering the machines stable in divers air currents, and the means of attaining the desired stability are usually classified under two heads, first the design and arrangement of the sustaining surfaces which result in a certain amount of inherent stability and secondly the construction of movable surfaces whereby a controllable stability is effected. These considerations are pertinent to this invention which is chiefly concerned in producing an extremely stable monoplane and to this end has undertaken the improvements in aerofoil design as well as aileron and wing tip arrangement to 75 be hereinafter disclosed.

Considering first well-known aerofoil structure, what is known as the "dihedral angle" or V-form of monoplane such as has been experimented with in the "Antoinette" 80 type has been found to possess certain advantages particularly when the machine is volplaning, and certain authorities pronounce it an improvement as regards sustaining power. Certain disadvantages however, have arisen in this type due to the great strain upon the wing tips which has often resulted in the buckling of the latter upon the giving way of the lower ties and the consequent destruction of the machine. 90 It is therefore proposed by this invention to incorporate the advantages of this type of aerofoil construction while doing away with its faults in the manner to immediately appear.

In Figs. 1, and 2, there is shown an aerofoil comprising a central portion formed of the two inwardly and upwardly arching planes 5 and 6 whose meeting line lies in the central longitudinal vertical plane of the machine so that a somewhat arcuate dihedral angle is formed which is the reverse of that usually employed where as is well known the planes incline downwardly and inwardly to a meeting edge. The surfaces 100 of the planes are smaller than those usually found in machines of this type and arch above the chassis. The width of these planes increases as they rise to their meeting point as is clearly illustrated in Fig. 2 for a pur- 110

pose to be hereinafter mentioned. The span webs 7 support the mentioned planes and in addition carry a pair of aerofoils 8, one of which adjoins each of the mentioned 5 planes 5 and 6 at their base line and is there maintained by ribs 9. Wing tips 10 of substantially the same size as the arched planes and similarly increasing in width with upward progress are maintained in juxtaposition to the outer edges of the planes 8 by the 10 pairs of outrigger rods 11 which also serve to support the extremities of the webs 7 by means of the metallic angle plates 12 which latter are formed with an intermediate step 15 portion and terminal wings, the former sustaining the webs 7 and one each of the latter connected respectively to the wings 10 and rods 11. The connection between the forward plates 12 and the mentioned wing 20 tips is preferably slightly loose in order to provide for the warping of the forward edges of the wing tips which is accomplished by means of a flexible connection 13 operable by the monoplane pilot to act upon 25 the projecting end 14 of the warping lever 15 carried along the lower edge of each wing tip. Pulleys 16 are arranged upon the frame members 7 in order to permit of a normal pull by the connections 13 upon the 30 lever ends 14. From thence these connections run to eye bolts 17 in order to be horizontally directed to the ends of the control lever 18 which is pivoted transverse on the chassis members 19 immediately below a 35 driver's seat 20 also supported on the members 19 in order that the said control lever may be operated by the feet or knees of the pilot. As a means for preventing movement of the rear portion of the wing tips 40 when it is intended to warp the forward edge, rigid stays 21 are provided supported at one extremity by the ribs 9 and connected at the other to the upper rear end of each wing as a reliable prevention of a buckling 45 on the part of these aerofoil members. A connection 22 fastened to the upper forward portion of each wing tip serves to cause coordinate action and the simultaneous movements of the wing tips when either one is 50 operated.

As to the construction of the various planes any suitable fabric 23 may be stretched upon the ribs 24 in any well-known and usual manner.

55 The fuselage of the machine includes the mentioned chassis frame members 19 which converge downwardly and forwardly to support the single forward wheel 25 and which are rearwardly connected as at 26 to the 60 horizontal fuselage members 27 which are also connected at their front extremities with the frame rods 19 by means of struts 28 and which support intermediately the engine 29 and fuel tank 30, the former being 65 provided with a cased drive shaft 31 having

secured at the extremity thereof the propeller 32 positioned in the usual forward situation common to monoplanes.

Chassis members 33 extend similarly from the members 27 in a diagonal manner to support the rear wheels 34 being braced adjacent thereto by a suitable means 35. Lower fuselage frame members 36 converge rearwardly to support with the similar members 27 the rudder post 37 to which is pivoted the rudder or tail fan 38 in suitable hinge brackets 39. As a controlling means for the rudder, there is provided a flexible connection 40, each end of which is secured as at 41 to opposite sides of the rudder and 75 centrally thereof, the said connections extending laterally from their fastening point to the tail by traveling over pulleys 42 mounted in the end laterally directed braces 43 secured to the upper fuselage members 80 27 and further braced by the transverse stay 44. Leading forwardly from the pulleys 42 the connections 40 pass through the eye bolts 17 to pulleys 45 carried on the extremities 85 of a pivoting pin which mounts the control 90 lever 46. This lever 46 has a longitudinal swaying movement and is bifurcated at its upper end in order to receive the tail controlling wheel 47 which is circumferentially grooved to receive the central bight of the 95 flexible connections 40.

The forward and rearward movement of the control lever is designed for operating the following tail plane 48 by means of the flexible connections 49 secured to the lever 100 on opposite sides of the pivoting point and passing rearwardly thence to respective pulleys 50 carried by the cross brace 44 and the tail post 37 to vertically direct the connections 49 to a common point of fastening in the retaining eye 51 carried by the tail plane 48. This tail plane consists of a pair of substantially triangular lateral wing portions 52 formed similarly to the described planes and connected by a like metallic central web 105 53. The forward or entrant portions of this tail plane are slightly cambered and reinforced by rod braces 54 which are held taut by struts 55. Pivoting plates 56 are formed with suitable eyes 57 adapted to receive the 110 transverse pin 58 which is supported by uprights 59 secured to and bracing the fuselage members 27 and 36 in the manner indicated in Fig. 3.

The foregoing description covers a sufficiently detailed disclosure of the present invention to permit recognition of the novel departure from customary monoplane construction herein contained. It will be noted that what has been termed side slip—which 125 may be briefly explained as that tendency of the air to take the path of least resistance upon encountering an obstacle, which results in an attempt to escape laterally as well as over the forward and rear edges—may be 130

effectually prevented by the various dihedral angles formed between the planes 8 and 5, 8 and 6, and 8 and 10, as these tend to check lateral slipping off of the air and accordingly increase the efficiency of the lifting surface as a whole which accomplishes what was previously considered desirable under the heading of automatic stability. Controllable stability is attained by means of the warpable wing tips and the movable tail plane both having their functions too well-known to necessitate discussion in this art and both being simultaneously controllable by the pilot without his being forced to re-
move his hands from the rudder control 47.

It is to be particularly noted that a close association exists between the arrangement of the warpable wing tips and the structure of the aerofoil permitting the wing portions to partake of the nature of both automatic and controlled stability a novel feature of unquestioned advantage in the structure of modern flying machines.

While in the foregoing however, there has thus been illustrated in the drawings, and described in the specification, such combination and arrangement of elements as constitute the preferred embodiment of this invention, it is desired to emphasize the fact that such minor changes in the matters of proportion and degree may be made in later adaptations of this device as shall not alter the spirit of the invention as defined in the appended claims.

35 What is claimed is:

1. In an aeroplane, arched main planes forming a dihedral angle, intermediate horizontal planes, and outwardly inclined planes carried at the ends of said intermediate planes, the width of said first and last planes increasing upwardly.

2. In an aeroplane, an aerofoil including arched central planes, intermediate planes connected to said arched planes at their bases, outwardly inclined wing planes at the ends of said intermediate planes, a lever extremity carried by the forward edge of each of said wing planes, means for bracing the rearward edge of each of said wing planes, and means connecting with said lever extremities for warping said wing planes.

3. In an aeroplane, an aerofoil structure including spaced webs, arched planes centrally supported upon said webs, wing planes carried at the extremities of said webs in outward inclination, an intermediate horizontal plane resting directly upon said webs between each of said arched planes and a wing plane, a lever extremity carried by the forward edge of each wing plane, a brace extending from one of said webs to the rearward extremity of each of said wing planes, and means connecting with said lever extremities for manual warping of the forward edge of said wing planes.

4. In an aeroplane, an aerofoil including arched central planes, intermediate planes connected to said arched planes at their bases, outwardly inclined wing planes at the ends of said intermediate planes, a lever 70 extremity carried by the forward edge of each of said wing planes, means for bracing the rearward edge of each of said wing planes, means connecting with said lever extremities for warping said wing planes, and 75 means coördinating the action of said wing planes when warped.

5. In an aeroplane, an aerofoil structure including spaced webs, arched planes centrally supported upon said webs, wing 80 planes carried at the extremities of said webs in outward inclination, intermediate planes resting directly upon said webs between each of said arched planes and a wing plane, a lever extremity carried by the 85 forward edge of each wing plane, a brace extending from one of said webs to the rearward extremity of each of said wing planes, means connecting with said lever extremities for manual warping of the forward 90 edge of said wing planes, and means coördinating the action of said wing planes when warped.

6. In an aeroplane, a plane supporting structure including rearwardly converging 95 fuselage members in pairs, means bracing said members, webs transversely supported by the uppermost pair of said members, an aerofoil structure including arched planes centrally supported upon said webs, wing 100 planes supported at the extremities of said webs, an intermediate plane between each arched plane and wing plane, an operating lever pivoted to one pair of said fuselage members, a lever extremity prolonged upon 105 the forward edge of each of said wing planes, a brace between one of said webs and the rearward edge of each wing plane, and flexible connections between each lever extremity and said operating lever for 110 warping the forward edge of such planes.

7. In an aeroplane, a plane supporting structure including rearwardly converging fuselage members in pairs, means bracing 115 said members, webs transversely supported by the uppermost pair of said members, an aerofoil structure including arched planes centrally supported upon said webs, wing planes supported at the extremities of said webs, an intermediate plane between each 120 arched plane and an end plane, an operating lever pivoted to one pair of said fuselage members, a lever extremity prolonged upon the forward edge of each of said wing planes, a brace between one of said webs and the rearward edge of each wing plane, flexible 125 connections between each lever extremity and said operating lever for warping the forward edge of such planes, and means connecting the forward edges of said wing 130

- 4
- planes at points opposite to the lever prolongation for coördinating the warping action of such planes.
8. In an aeroplane, a fuselage including 5 members, rearwardly converging in pairs, struts bracing said members, frame members connected to both pairs of said members, a lever pivoted for longitudinal movement between said frame members, a wheel 10 rotatably mounted in said lever, a tail-plane pivoted to two of said struts at its forward central edge, pulleys carried at the rear of said fuselage, and a flexible connection attached to said tail-plane passing above and 15 below the pivotal axis of the same, over the respective pulleys and thence forward to be connected to opposite sides of said lever from the pivot point thereof.
9. In an aeroplane, a fuselage including 20 frame members rearwardly converging in pairs, struts bracing said members, a pair of chassis frame members connected to each pair of said fuselage members, a rudder post carried by said first frame members, 25 a rudder horizontally movable on said post, a tail-plane centrally pivoted to a pair of said struts, a lever pivoted between said chassis frame members, a wheel rotatably mounted within said lever, flexible connections 30 oppositely leading from said tail-plane to opposite points of said lever, and similar flexible connections leading from opposite sides of said rudder and having a bight portion thereof receivable over said wheel.
10. In an aeroplane, a fuselage including 35 frame members converging rearwardly in pairs, a rudder post supported by said frame members, chassis frame members connected to each pair of said fuselage frame members, a lever pivoted between said chassis frame members, a wheel rotatably carried by said lever, webs transversely supported by one pair of said fuselage frame members, wing planes carried at the extremities of said web, the forward edge of each of said planes terminating in a lever extremity, a brace between one of said webs and the rearmost edge of each of said wing planes, an operating lever pivoted to said chassis members adjacent said first-mentioned lever, flexible connections between said lever, extremities on the wing planes and said operating lever, a tail-piece pivotally mounted at the rear of the fuselage, 40 flexible connections between said tail-plane and said first-mentioned lever, a rudder, flexible connections between said rudder and said wheel having a central bight thereof receivable thereover, and a flexible connection between the forward edges of said wing planes for coördinating warping action 45 thereof.
